UNITED STATES PATENT OFFICE

HARRY H. FISHER, OF GREEN BAY, WISCONSIN

APPARATUS FOR DRIVING TUNNELS

Application filed February 3, 1926. Serial No. 85,730.

My invention relates, more particularly, to the driving of tunnels through material required to be blasted; and my primary object is to materially reduce the cost of tunneling and expedite the tunneling operation to the end that the time required for driving the tunnel will be greatly reduced. Specifically stated, one of my objects is to provide for the driving of the tunnel with the expenditure of less amounts of explosives than heretofore required; and to minimize the number of operations required for handling the material displaced in the blasting operation, resulting in the reduction of labor costs and expediting the tunneling operation.

Referring to the accompanying drawings:

Figure 1 is a longitudinal sectional view in elevation through the head end of a tunnel which is being driven in accordance with my improved method and involving the use of apparatus involving my invention, only that portion of the apparatus which is located closely adjacent to the face portion of the tunnel being shown in this figure, the receiver portion of the apparatus being shown by a view in longitudinal sectional elevation taken at the line 1-1 on Figure 2 and viewed in the direction of the arrows. Figure 2 is a plan view of the portion of the apparatus shown in Fig. 1. Figure 3 is a view like Fig. 1 and forming a continuation thereof, this view showing two of the cars employed for removing the sections of the receiver, this view showing the innermost and intermediate sections of the receiver in a position in which they are withdrawn from the position shown in Fig. 1, these sections being shown by views in vertical longitudinal section. Figure 4 is a plan view of the portion of the apparatus shown in Fig. 3. Figure 3^a is a continuation of the tunnel structure and apparatus shown in Fig. 3, this view showing the outermost one of the receiver sections in vertical longitudinal section and the cars upon which this section, and also the hauling mechanism, are carried. Figure 4^a is a plan view of the portion of the apparatus shown in Fig. 3^a. Figure 5 is 50 an enlarged, broken view in vertical longi-

tudinal sectional elevation of that portion of the apparatus shown at the right-hand side of Fig. 1. Figure 6 is a view in end elevation of the portion of the apparatus shown in Fig. 1, the structure being viewed from the right-hand end of this figure. Figure 7 is an enlarged section taken at the line 7-7 on Fig. 3 and viewed in the direction of the arrows, with the upper portion of the receiver-section therein shown, broken away. Figure 8 is a view somewhat in the nature of a diagram of the supporting structure for the receiver illustrated in Fig. 1 and illustrating the means employed in the illustrated embodiment of my invention, for preventing friction between the sections of the receiver in the operation of separating these sections; and Figure 9, a view like Fig. 1 showing a modification of the arrangement of the explosive charges in the face portion of the tunnel, and a modification of the apparatus for removing the displaced, blasted, material.

Referring to the tunneling operation and the apparatus for producing the same, shown in Figs. 1 to 8, inclusive, a tunnel in the process of being formed is illustrated at 10, Fig. 1 showing by the dotted lines 11 the face of the tunnel before the blasting thereof by explosive charges positioned in the drill holes 12, and by full lines the face portion of the tunnel after these charges have been fired. In accordance with this feature of the invention the face portion instead of being substantially vertical throughout its height is generally inclined downwardly from the top of the tunnel in a forward direction to a point slightly above the floor of the tunnel and from this point downwardly is substantially vertical, as shown, the drill holes 12 extending substantially at right angles to the portions of the face in which they are located. In other words, the drill holes 12 in the inclined portion of the face extend generally in an upward and forward direction and the drill holes in the vertical face extend generally in a horizontal direction. This feature of the invention which is of great utility in connection with the apparatus hereinafter described, but

which also has great usefulness irrespective of such apparatus, is of great value inasmuch as the amount of explosive required to be used in blasting a given amount of material is much less than if the face of the tunnel were vertical throughout its height, as the force required to blast the overhead material is considerably less than that required for blasting the material at a vertical face.

Referring now to the apparatus illustrated, the tunnel 10 is equipped with a railway track 13 shown as extending forwardly short of the face of the tunnel and upon which cars, hereinafter referred to, are adapted to be run. Located at the inner end of the track is a supporting structure represented generally at 14 for a receiver hereinafter described, this supporting structure being shown as formed of a bottom plate 15 at which the structure is adapted to rest upon the floor of the tunnel; an upper forwardly and downwardly inclined plate portion 16 and supporting girders 17 interposed between these plates and rigidly secured thereto in any desired manner, these girders being of tapered form to support the plate 15 in the forwardly and downwardly inclined position as stated.

The supporting structure 14 is provided to support the receiver heretofore referred to and represented generally at 18 which, when in the operative position shown in Fig. 1, is positioned to receive the blasted material when it is discharged downwardly and rearwardly by exploding the charges in the drill holes 12. The receiver shown is of general trough-form in cross section throughout its length and open at its forward end, it being formed of a plurality of sections arranged in a series extending lengthwise of the receiver. In the particular embodiment shown in the figures of the drawings now being described, the receiver is formed of two end sections 19 and 20 and an intermediate section 21, the forward end section being so shaped, as shown, that it may extend close to the vertical portion of the face of the tunnel. The bottom portion of the receiver-section 19 is formed of two superposed plates 22 and 22^a, the lowermost plate 22 extending rearwardly beyond the rearward edge of the plate 22^a a considerable distance as shown. The bottom portion of the intermediate section 21 is formed of two plates 23 and 24, the plate 23 extending rearwardly beyond the plate 24 and the plate 24 extending forwardly beyond the plate 23, the forward portion of the plate 24lapping the rear portion of the plate 22. The bottom portion of the section 20 is formed of two plates 25 and 26 the plate 25 extending rearwardly beyond the plate 26 and the plate 26 extending forwardly beyond the plate 25 and lapping the rear portion of the

plate 23. The bottom portion thus formed is, by reason of the offsetting and lapping of the plates as described, practically flat throughout its under surface as shown. The side walls of the receiver sections 19, 20 and 21 are also formed of double thickness throughout portions of their length except where the side walls of adjacent ones of the sections lap, as illustrated, to provide a substantially flat surface along the inner sides 75 of the side walls of the receiver sections.

The sections 19, 20 and 21 when assembled to the position shown in Fig. 1 form a single receiver upon which the blasted material discharges as for example, generally to the position shown in this figure, wherein the material is represented at 27, these sections being separable, each for supporting a portion of the mass 27 of blasted material, by relative movement of these sections lengthwise 85 of the receiver structure, the provision of the lapped bottom and side walls adapting these sections to retain thereon the entire load of material, when these sections are separated as stated, thus avoiding the dropping of the 90 material from these sections.

The receiver-sections, after becoming charged with the blasted material, are successively drawn backwardly from the position shown in Fig. 1, preferably to a position 95 in which each is supported on a separate car located on the track 13, and to facilitate the movement of the sections to the assembled position shown in Fig. 1 and to the disassembled position in which they are supported on 100 the cars referred to, the supporting structure 14 is provided with rollers 28 journaled on the supporting structure at opposite sides thereof. The rollers 28 are directly supported on girders 29 extending lengthwise 105 of the structure 14, one at each side thereof and located in spaces defined by the plates 15 and 16 and certain of the girders 17, the plate 16 containing apertures 30 registering with the respective wheels 28. Inasmuch as great 110 force will be exerted against the receiver 18 in the discharge of the material into it, it is desirable that the rollers 28 be withdrawn from a position in which they support the receiver and that the receiver rest directly on 115 the heavy, highly resistant, plate-like top portion of the supporting structure 14 during the blasting operation. To this end the girders 29 are so mounted that by shifting them lengthwise in one direction or the other, the rollers 28 will be moved into or out of a position in which they engage with the bottom portion of the receiver. In the particular arrangement shown each girder is provided at its underside with blocks 31 having 120 flat horizontal bottom surfaces at which these girders engage with the upper flat horizontal surfaces of cross members 32 extending between, and rigidly secured to, the girders 17 between which the girders 29 are lo- 125 130

cated whereby when the girders 29 are in the position shown in Fig. 8 the rollers 28 extend below, and out of contact with, the bottom portions of the receiver sections, and when these girders are shifted to the left in Fig. 1, these rollers are forced against the bottom portion of the receiver sections and into a position in which the latter are supported on the rollers. As a suitable means for thus operating the girders 29, I provide the mechanisms shown which comprise shafts 33 having threaded connection with the rearmost one of the cross members 32 with rotatable connections between their forward ends and with brackets 34 depending from the girders 29, the shafts 34 being held against movement lengthwise in these brackets by stop means 35 on the shafts 33. The shafts 33 are rotated in either direction, as desired, by any suitable means, as for example lever-operated ratchet mechanisms represented generally at 36.

It is desirable that the lapped bottom portions of adjacent receiver sections, be out of engagement with each other prior to the operation of separating these sections, to avoid the frictional resistance which would otherwise be present, and to this end I so position the various rollers 28 that when these several rollers are in raised position, the lapped bottom portions referred to will be out of contact with each other, as shown of the forward end portion of the plate 26, relative to the rear portion of the plate 23, and as represented diagrammatically in Fig. 8 as to the bottom portions of all of these sections. This is effected in the particular construction shown by so positioning those of the rollers 28 which engage the bottom portion of the section 20 that they extend a greater distance through the openings 30 than in the case of those of the rollers 28 which engage the bottom portion of the intermediate section 21, and so dispose these last-referred-to rollers that they extend through the openings 30 a greater distance than the rollers which engage the bottom portion of the forwardmost section 19. In this connection it may be stated that the fuel lines in Fig. 8 represent the rollers in the position they occupy when they are withdrawn from a position in which the receiver is supported thereon, and by dotted lines the position they occupy when raised to support the receiver.

Assuming that the receiver has received the body 27 of material displaced by the blasting operation, and that the operator has shifted the girders 29 to the right in Fig. 1 to a position in which the receiver sections are supported on the rollers 28 as explained, the rear section 20 of the receiver is first drawn rearwardly out of a position in which it is telescoped with the intermediate section 21, as for example by means of cable mechanism represented generally at 37 which is hooked

to the rear end of the section 20 and is operated by any suitable drum mechanism represented generally at 38 and mounted on a car 39 positioned on the track 13. The section 20 is drawn up the supporting member 14 and along the roller-equipped portions 40 of other cars 41 and 42 supported on the track 13, and thence along the roller-equipped portion 40 of another car 43 on which this section is to be carried to the point of discharge. The cables 37 are then connected with the rear end of the intermediate receiver sections 21 and this section then drawn up the supporting structure 14 and across the car 41 to carrying position on the car 42, and thereupon the forward section 19 is drawn upwardly to carrying position on the car 41, the cars referred to and coupled together being then moved along the track to the point of discharge, where the various receiver sections may be relieved of their contents in any desirable manner.

In order that spilling of the material from the various separated sections, be entirely obviated, it is preferred that the bottom plate portion of each receiver section, at its ends be provided with boards represented at 44 which may be provided as structures separate from the sections and removably held in place by abutment pins 45 projecting upwardly from the bottoms of the sections.

Referring to Fig. 9 wherein I have shown a slight modification of the arrangement of explosive charges and a modification of the apparatus for disposing of the blasted material, the face of the tunnel, instead of being substantially plane at its inclined portion, as represented in Fig. 1, is shown as of stepped form and the charges for blasting the material are located in drill holes provided in a series of groups represented at 45, 46 and 47, and located in a different horizontal plane, with each group segregated from the others. This arrangement, which, however, is within my invention, results in the blasting, with each blasting operation, of a plurality of overhead sections 48, 49 and 50 in different planes, but in a downward direction to a receiver, the sections 48, 49 and 50 being bounded by the dotted lines 51, 52 and 53. The effect of providing the overhead face of the tunnel and grouping the drill holes as shown and described is substantially the same as in the construction shown in Fig. 1 and the benefits of blasting the materials generally in a downward direction throughout the greater portion of the face of the tunnel, results from such method of tunnel blasting.

The receiver member illustrated in this Fig. 9, instead of being of the telescoping trough type shown in the preceding figures, is formed of a longitudinal series of boxlike sections 54, 55 and 56 having open tops, and with the forwardmost end portion 57 of the

section 54 open to receive the material blasted from the substantially vertical portion of the face of the tunnel, the receiver sections referred to cooperating with a supporting structure 58 of the general character hereinbefore described, the rollers 7 (not shown), need not be located in different planes as described of the rollers 28, inasmuch as the sections 54, 55 and 56 are not provided with lapped portions which, if spaced apart, would produce objectionable friction in the displacement of the receiver sections from the material-receiving position shown in Fig. 9.

15 It will be understood that, as the driving of the tunnel progresses, the track 13 will be extended forwardly and the supporting structure for the receiver, accordingly advanced, to cause the receiver member to extend in the most advantageous position.

20 Any suitable means adapting the supporting structure to be advanced may be employed, as for example that shown in Figs. 1 to 8, inclusive, and comprising jacks 58 secured to, 25 and arranged at intervals along, the opposite sides of the supporting structure 14 and each provided with a flanged wheel 59 extending above a track 60 below it, the wheels 59 being rotatably mounted in bearing heads 61 adjustable up and down, as for example by means of threaded shafts 62 having threaded engagement with stationary bearing heads 63 on the structure 14. The jacks are so disposed that when in one position the 30 structure 14 rests flatwise against the floor of the tunnel and when adjusted to another position, by rotating the shaft 62, the structure 14 is supported wholly through the medium of the wheels 59 adapting the structure 35 to be readily shifted into and out of a position adjacent the face of the tunnel.

40 It will be understood that the method and apparatus according to my invention may be employed not only in tunneling operations for driving bores, as in the case of road or 45 railway tunnels, but also in tunneling operations performed in mining.

While I have illustrated and described my improved method as practiced in certain 50 particular ways and have shown certain constructions of apparatus embodying my invention, I do not wish to be understood as intending to limit it thereto, as various modifications, changes and alterations may be 55 made in the apparatus and the method variously altered without departing from the spirit of my invention.

What I claim as new, and desire to secure by Letters Patent, is:

60 1. In apparatus of the character described, the combination of a receiver member positioned to have material blasted directly into it, a stationary supporting member therefor, and wheels carried by one of said members and adjustable up and down thereon into

and out of a position in which said receiver member is supported at said wheels.

2. In apparatus of the character described, the combination of a receiver member positioned to have material blasted directly into it, a stationary supporting member therefor, 70 wheels carried by one of said members and adjustable up and down thereon into and out of a position in which said receiver member is supported at said wheels, and means for adjusting said wheels up and down. 75

3. In apparatus of the character set forth, the combination of a stationary supporting member comprising a body portion and wheels thereon adjustable into and out of a position for supporting a receiver positioned on said supporting member, said body portion, when said wheels are adjusted to withdrawn position, forming a direct support for 80 said receiver.

4. In apparatus of the character set forth, the combination of a receiver member, a supporting member therefor having a forwardly and downwardly inclined upper surface, and wheels on one of said members adjustable 85 up and down thereon into and out of a position in which said receiver member is supported at said wheels, said supporting member having a portion upon which said receiver member rests when said wheels are withdrawn from 90 supporting position.

5. In apparatus of the character set forth, the combination of a receiver member, a supporting member therefor having a forwardly and downwardly inclined upper surface, 100 and wheels on said supporting member and disposed in a series substantially forwardly and downwardly inclined and adjustable up and down on said supporting member into and out of a position in which said receiver 105 member is supported at said wheels.

6. In apparatus of the character set forth, the combination of a supporting member, a receiver member thereon formed of separable sections arranged in a series extending 110 lengthwise of said receiver member with the bottom plates of adjacent sections lapped in the assembled condition of said sections, and members on said supporting member at which said receiver member is supported, 115 said last-referred-to members being arranged at such heights relative to each other that the lapped bottom-plate portions of said receiver sections will extend out of a position in which they frictionally engage with 120 each other in the separation of said sections in a direction lengthwise of said receiver member.

7. In apparatus of the character set forth, the combination of a supporting member, a receiver member thereon formed of separable sections arranged in a series extending 125 lengthwise of said receiver member with the bottom plates of adjacent sections lapped in the assembled condition of said sections, and 130

wheels on said supporting member at which said receiver member is supported, said wheels being arranged at such heights relative to each other that the lapped bottom plate-portions of said receiver sections will 5 extend into a position in which they do not frictionally engage with each other in the separation of said sections in a direction lengthwise of said receiver.

8. A receiver comprising separable trough 10 sections disposed in a series extending lengthwise of the receiver, with the bottom and side portions thereof in lapped relation, those of the bottom-lapped portions which 15 are uppermost being upwardly offset relative to the remainder of the bottom portions of which they are parts.

9. A receiver comprising separable trough 20 sections disposed in a series extending lengthwise of the receiver, with the bottom and side portions thereof in lapped relation, those of the bottom-lapped portions which 25 are uppermost being upwardly offset relative to the remainder of the bottom portions of which they are parts and those of the side-lapped portions which are innermost being inwardly offset relative to the remainder of the side portions of which they are parts.

10. In apparatus of the character described, 30 the combination of a receiver member positioned to have material blasted directly into it, a stationary supporting member therefor, wheels between said receiver member and said supporting member and by 35 which said receiver member is supported on said supporting member in the movement of said receiver member along said supporting member, and means whereby said wheels may be relieved of the forces exerted against 40 said receiver member in receiving the blasted material.

11. In apparatus of the character set forth, 45 the combination of a receiver member, a supporting member therefor having a forwardly and downwardly inclined upper surface, wheels between said receiver member and said supporting member and by which said receiver member is supported on said supporting member in the movement of said receiver member along said supporting member, and 50 means whereby said wheels may be relieved of the forces exerted against said receiver member in receiving the blasted material.

HARRY H. FISHER.
